UNITED STATES PATENT OFFICE.

HOWARD VAN SCOV, OF CHICAGO, ILLINOIS.

SWITCHING AND BRAKING DEVICE.

1,405,562.

Specification of Letters Patent. Patented Feb. 7, 1922.

Application filed January 8, 1921. Serial No. 435,819.

To all whom it may concern:

Be it known that I, HOWARD VAN SCOV, a citizen of the United States, residing at Chicago, in the county of Cook and State of Illinois, have invented certain new and useful Improvements in a Switching and Braking Device, of which the following is a specification.

This invention relates to railways, and pertains particularly to appliances for controlling the speed of cars independently of their braking apparatus while they are being shunted or moved separate from a locomotive or other propelling means.

As is well known in present day railway practice, it is customary in many instances in so called gravity yards, to distribute cars in the process of making up different trains by cutting them loose individually or in groups on a main switching track at the top of a grade or hump so they will travel down the grade under the influence of gravity, and then turning them on to desired sidings or shunt tracks through switches from the main track. Such yards are laid out on proper grades to cause the cars to continue to travel on the sidings under the influence of gravity until stopped by a bumper or by coming up against other cars ahead of them on the sidings. In present practice, the speed and movement of the cars is controlled by hand manipulation of the braking apparatus on the several cars, and this necessitates a brakeman riding each car during the course

of its movement in order to manipulate the brakes, thereby to control its speed and prevent violent or destructive impact upon the bumper or the car ahead of it upon the siding. In the event of failure or inoperativeness of the brake mechanism of the car, there is no way of controlling its speed, and in such contingencies the operation is dangerous to both the workman and the equipment.

The general object of the present invention is the provision of means which may be installed as part of the yard equipment and the operation of which may be controlled from a central station or tower and which will be effective automatically to control the speed of individual cars during such periods of their movement on the tracks as may be desired.

Another purpose of the invention is the provision of such apparatus which may be rendered effective in conjunction with the operation of switches which govern the

movement of the cars onto the selected sidings.

Another object of the invention is the provision of such apparatus which may be operated manually at selected points in the course of the cars' travel.

A still further object of the invention is the provision of such apparatus which is operable selectively to determine the extent of its braking effect upon the cars.

Other and further objects of the invention will be pointed out hereinafter, indicated in the accompanying claims, or obvious from the following description and the drawings forming a part of this specification. The invention will be disclosed through the following description of an illustrative embodiment, it being understood that the same comprises but one of various forms in which the invention may be incorporated, and that the mechanism utilized may be changed by adaptation and substitution without sacrifice of the essential features and principles constituting the essence of the invention.

In the said drawings,

Fig. 1 is a plan view of fragmentary track sections illustrating the association of various elements of the car braking apparatus;

Fig. 2 is a plan view of a track section and switch points illustrating the association of the invention with the same;

Fig. 3 is a transverse section of a track portion showing the mounting of the throw-off incline;

Fig. 4 is a side elevation of mechanism illustrated in Fig. 1;

Fig. 5 is a detail showing side elevation of the braking shoe;

Fig. 6 is a side elevation of the shoe block with parts broken away;

Fig. 7 is a detail in the nature of a section on line 7—7 of Fig. 5;

Fig. 8 is a plan view of the shoe mechanism;

Fig. 9 is a side elevation of the same;

Fig. 10 is a section of a rail showing an end elevation of the throw-off cam;

Fig. 11 is a longitudinal section of the shoe mechanism showing it in cooperation with the rail;

Fig. 12 is a sectional view of the shoe mechanism and its mounting, showing the former retracted from the rail;

Fig. 13 is a section similar to Fig. 11 illustrating the cooperation of the lifting incline with the shoe;

Fig. 14 is a side elevation showing the parts in the relationship illustrated in Fig. 13;

Fig. 15 is a top view partly in section illustrating the operation of the throw-off cam;

Fig. 16 is a plan view illustrating the operative connections between the cast-off mechanism and movable switch portions;

Fig. 17 is a longitudinal section of a track portion showing in elevation certain of the parts illustrated in Fig. 16; and Fig. 18 is a plan view of a modified form of actuating means.

Described generally the invention contemplates the provision of a shoe guide in the nature of a rail disposed alongside a selected stretch of the railway track on which the cars are to be shunted, upon which guide is mounted a travelling shoe adapted to be moved into cooperation with a rail of the track at selected points. When so positioned in cooperation with the rail, the shoe occupies a position where it will engage a wheel of a car travelling on the track in such fashion that the shoe will be carried along by the car and, due to its frictional drag on the rail, will be effective to exercise a braking action which will control the speed of the car. At the point where the braking influence is to be removed, devices are installed for disengaging the shoe from the wheel of the car and from the rail of the track so as to permit its lateral withdrawal automatically to an ineffective position where it is supported by the shoe guide. Automatically effective means is supplied whereby, when the shoe is disengaged from the track rail, it is withdrawn back to the point at which it was originally engaged with the track rail, in which position it is ready for replacement upon the track rail when desired. Means adapted for operation either from a central station or switching tower, or manually at selected points, is provided for effecting the positioning of the shoe upon the track rail, and for positioning the throw-off devices whereby the shoe is disengaged from the track rail, so that they may be rendered effective to accomplish that operation. Or the throw-off devices may be operably associated with track switch portions in such fashion that they are moved to operative and inoperative positions in accordance with the positioning of the switch portions.

Described more specifically, and with reference to the forms illustrated in the drawings, let it be understood that the reference character T designates railway track rails in association with which are installed shoe guides illustrated as comprising upper and lower channel members 1 supported on brackets 2 anchored on portions of ties beside the track rails. These shoe guides may be of any desired length, depending upon the selected extent of travel permitted for

the shoes. Such guides may be disposed on opposite sides of the track, if desired, such an arrangement being illustrated in Fig. 1, whereas in Fig. 2 the disposal of a guide at only one side of the track is shown. Mounted on the shoe guide is a braking device, the construction of which is best illustrated in detail in Figs. 8 to 15 inclusive. This braking device includes a shank portion 4 which is a substantial rigid member of sufficient length to extend from the shoe guide to the adjacent track rail, and which has opposite parallel faces adapted to ride between the members 1 of the guide, whereby the shank is maintained in substantially horizontal position while permitted freedom of movement longitudinally toward the track rail and transversely throughout the extent of the guide. A block 5 is provided with an aperture which accommodates the shank member 4, and carries antifriction rollers 6 effective at its inner side, so that when the block is in operative position said rollers will ride upon the outer vertical flanges of the channel members 1. Carried at the inner extremity of the shank member 4 is a stop portion 7 extending beyond the upper and lower surfaces of the shank and equipped with anti-friction rollers 8 adapted to contact the inner vertical flanges of the rail members 1 when the braking device is retracted, and thereby limit outward movement of said device. Coiled springs 9 are connected at their extremities to the block 5 and stop member 7, passing between the upper and lower channel members 1, and said springs have the tendency to hold the shank member retracted with the rollers 8 of the stop member against the inner vertical flanges of the channel members. At the inner extremity of the shank 4 adjacent the stop member 7 is supported a head member 10 which, together with the stop member 7, may be formed integrally with the shank 4. The construction of this head member is best illustrated in Fig. 6, wherein it will be seen that it is in the nature of a block having its rearward and lower faces grooved to form a shoe seat 10^a between lateral flanges or shoulders. The head 10 forms a mounting for the shoe 11 which has a rib 11^a adapted to fit in the shoe seat of the head, said rib including an enlargement or boss 11^b at its upper extremity adapted to interfit a depression 10^b in the shoe seat, and a transversely apertured boss 11^c adapted at its forward extremity to register in a recess 10^c of the shoe seat, wherein it may be retained by a bolt, rivet or the like. The shoe includes a base or friction plate 11^d of proper width to make substantial bearing contact with the surface of the head of the track rail, from which friction plate depends a guide flange 11^e adapted to contact the outer lateral face of the rail head. The

rearward portion of the shoe extends a substantial distance from the rib 11^a and is formed with an arcuate wheel engaging portion 11^c to which the lower surface of the 5 friction plate is tangent. On the inner side of the head member 10 is supported a latch plate 12, the same being adapted for vertical movement on the head member to an extent permitted by the slots 12^a through 10 which the fastenings 14 extend. This extent of movement is sufficient to permit the lower portion of the latch plate 12 to extend a substantial distance below the friction plate 11^d of the shoe, so that such portion of the 15 latch plate will be in position to engage the inner lateral surface of the rail head when the friction plate is resting on the rail, while the extent of upward movement of the latch plate 12 is sufficient to permit its 20 being raised to clear the upper surface of the rail. Extending inwardly from the latch plate is a contact block 15 whereby the latch plate may be lifted as hereinafter described, while an outwardly extending 25 post 16 is arranged to provide an engageable member whereby the latch plate may be lifted by means of a crowbar introduced between said post and the top of the head member.

30 From the foregoing it will be seen that the braking device is adapted for travel longitudinally of the guide and is also adapted for movement toward and from the adjacent track rail. Suitable means is provided for constraining the travel of the 35 braking device longitudinally on the guide, which means is effective to return it to its initial or starting position when it is free from other restraint. This restoring means 40 is here illustrated by a mechanism including a flexible connection or cable 17 which is connected at one end to the braking device and guided in a horizontal course alongside the guide by a sheave 18 around 45 which it passes, and from which it is led to an elevated sheave 19 carried on a post 20 or other suitable support, and by the position of which a weight 21 is effective upon the connecting member 17 to tend to 50 retain the braking device at its starting position. This starting position is toward the end of the brake guide which is first approached by a car in its movement down the grade of the track, and is determined 55 by the location of an abutment 22 which may be set at suitable points in the guide by means of securing means 24 so that it will make contact with the side of the block 5 nearest the restoring mechanism.

60 The mounting of the guide sheave 18 is such that it may change its angularity relative to the track in a horizontal plane, so as to accommodate itself to the changes in angularity of the cable 17 relative to the track 65 incident to movement of the braking de-

vice. In the normal or starting position of the shoe, which hereinafter will be referred to as a setting station, is provided an inclined plane 25 sloping from adjacent the upper surface of the rail to a point sufficiently low to engage the lower margin of the latch plate, said inclined plane being positioned between the brake guide and the adjacent track rail, as best illustrated in Figs. 8 and 11. At the setting station, outside of the brake guide, is disposed suitable setting mechanism, here represented by a pair of bell crank levers 26 and 27 fulcrumed respectively at 26^a and 27^a and connected by a link 28. The work arm of the 70 lever 26 carries an anti-friction roller 29 adapted to contact the outer extremity of the shank 4 when in its retracted or outer position, and operation of the lever 26 by power applied to its power arm will be effective to swing lever 26 to impel the shank 4 inwardly toward the track rail, against the influence of the springs 9. Upon such movement of the shank, the latch plate 12 will be lifted by riding up the inclined 75 plane 25 so that the friction plate of the shoe may be positioned on the head of the rail. When the latch plate has passed over the upper surfaces of the rail, it will fall so that its lower portion will engage the 80 inner face of the rail head, and thereby retain the shoe in alignment upon the rail. The braking device is thus placed in operative position, which is illustrated in Fig. 8, and in which position it will be engaged 85 by a wheel, indicated at W in Fig. 9, of a car shunted against it. The weight and cable will be effective to restrain the braking device in place so that a wheel so moved into cooperation with the shoe will ride up the rearward extension thereof to an extent where the tread of the wheel is lifted from the tread of the rail, without raising the wheel flange to clear the rail head, the weight of the wheel and its portion of the 90 load being supported upon the shoe. This cooperation of the braking device with the car and rail will have the effect of exercising a braking influence upon the movement of the car, due to the friction which is imposed by the sliding of the shoe upon the rail. The braking device, however, is free to move longitudinally upon the rail in this association with the wheel, so that the movement of the car will not be abruptly stopped, but such movement and the speed thereof will be held in proper control. Obviously, the setting of the braking device in the manner above described may be accomplished either by the manual operation 100 of the lever 27, or by an automatic or mechanical operation thereof as by energization of an electro-magnetic device 30, or by a cable connection C to a tower or central operating station as illustrated in Fig. 18. 105

110

115

120

125

130

Such movement of the braking device in cooperation with the car will be continued to the extent permitted by the arrangement of the throw-off mechanism. The throw-off mechanism is best illustrated in Figs. 10, 13, 14 and 15. At desired points beyond the setting stations, there are positioned for association with the rail upon which the shoe is adapted to ride, a latch lifting incline 31 and a cast-off cam 32. The lifting incline is disposed at the inside of the rail, while the cast-off cam is disposed at the outer side thereof. The upper margin 31^a of the lifting incline is slightly above the level 10 of the tread of the rail, while the inclined margin 31^b thereof is directed toward the setting station. The arrangement is such that upon the braking device reaching the lifting incline, the block 15 will ride up 15 the incline margin and onto the top margin 31^a, thereby lifting the latch plate 12 to an extent where it is no longer effective to retain the braking device against outward movement away from the rail. Being thus 20 freed, the tendency of the springs 9 will be to throw the head and shoe away from the rail. As the shoe is held by the car wheel, however, it is desirable to employ positive means for freeing it, which means is furnished in the cast-off cam 32. This cam has an effective vertical face which diverges from adjacent the outer lateral face of the rail head, at which point it is adapted to enter between the guide flange 11^c of the 25 shoe and the rail, deflecting the braking device outwardly away from the rail incident to its movement longitudinally thereon. The forward extremity of the flange 11^c may be bevelled as illustrated in 11^c 30 to facilitate this operation. This lateral deflection of the braking device will swing the shoe out of alignment with the wheel, and be effective to disengage it therefrom, so that the braking device may be withdrawn 35 fully to retracted position as illustrated in Fig. 12, by the springs 9. Upon the braking device being thus freed from the car, the restoring means represented by the weight 21 and connection 17 will be permitted to exert its effectiveness to withdraw the braking device rearwardly along the guide to the initial or setting station. As 40 illustrated in Fig. 1, the throw-off devices 31 and 32 are shown in fixed relationship to the rails, and it is obvious that they may be so disposed if desired, a suitable distance beyond the setting stations, or in advance of switches or other track parts. The installation of the throw-off devices, however, may be such as to permit their movement into and out of operative association with the rail. Such installations are illustrated in Figs. 2, 3, 16 and 17 wherein they are operably associated with movable 45 switch portions. It is obvious, however,

that they may be similarly operated independently of switch portions. As shown in the last mentioned figures, the lifting inclines and cast-off cams are shiftably supported upon a foundation plate 34 adapted for attachment to the track ties, guides 35 being provided for so mounting the members 31 and 32. The members 31 and 32 carry guide pins 36 which pass through guiding apertures in the web of the track rail with a freedom of movement permitting the shifting of the members 31 and 32 toward and from the rail. Such shifting of said members may be accomplished through a mechanism represented by the bell crank levers 37 and 38 pivoted respectively at 37^a and 38^a and connected by a link 39. The levers 38 may be swung by any suitable mechanical connection such as the bridle rod 40 connecting the switch points P. By such a connection the positioning of the throw-off mechanism may be accomplished conjointly with the opening and closing of the switch, or, if the operating connection for the throw-off devices is not operably connected with the switch opening mechanism, they may be positioned by independently operated means.

The operation of the apparatus has been described in detail above. In the customary employment of the apparatus, it will be understood that cars are shunted toward a setting station one or more at a time. If it is desired to render the braking mechanism at the setting station effective upon the car or cars, the setting mechanism 26, 27, 29, 30 is energized to place the shoe 11 upon the rail in front of the approaching car. The car upon contacting with the shoe will ride the latter along the rail, thereby introducing the desired friction between the car and the track to reduce the speed of the car. When the shoe reaches a throw-off station it will be automatically disengaged from the rail by engagement with the members 31 and 32 in the manner above described and returned to the setting station by the action of the return mechanism 19, 20, 21, where it remains in retracted position upon the guide 1 in position to be engaged by the setting member 29 when its employment is next desired.

It will be obvious that there may be a series of setting stations and throw-off devices associated with a given stretch of track, so that one braking device may be rendered effective upon a car if another braking device has been cast off, and that thereby a car may be subjected to successive braking operations in the course of its movement. Such a series arrangement of the mechanism is illustrated in Fig. 1, wherein two setting stations are shown with throw-off devices interposed between them. It is obvious also that a plurality of shift-

able throw-off devices may be disposed following any setting station, said throw-off devices being independently operable to determine the extent to which a braking device placed on the rail at the setting station shall be permitted to be effective upon a car. These several features of adaptability of the apparatus permit its being so installed and operated to secure the desired braking effect upon different cars, irrespective of differences in their weight and the resulting momentum of their travel, so that the final result of the employment of the apparatus will be to deliver all cars at the stopping point at safe and proper speeds. Due to the fact that the braking device is returned to the seating station immediately it is released from a car, the installation is adapted to handle cars as rapidly as they may be delivered along the track, while the fact that the operation of the apparatus is automatic permits its being controlled entirely from a central station or tower if desired.

I claim:

- 25 1. In a railway, a braking apparatus comprising the combination of a guide extending alongside the track, a braking device supported thereon for movement longitudinally thereof and toward and from the track, said braking device including portions arranged for cooperation with a track rail and a wheel of a car thereon, and means for moving the braking device on the guide.
- 30 2. In a railway, a braking mechanism comprising the combination of a guide extending alongside a stretch of track, a braking device supported for movement thereon, said braking device including portions arranged for cooperation with a track rail and a portion of a car supported thereon, means effective upon the braking device to move said portions into and out of cooperation with the rail, and means for moving the braking device on the guide longitudinally of the track.
- 35 3. In a railway, a braking mechanism comprising the combination of a guide extending alongside a stretch of track, a braking device movably carried thereon and having portions adapted for engagement with a track rail and a portion of a car thereon, means for engaging the braking device with the rail, and means for disengaging the braking device from the rail.
- 40 4. In a railway, a braking mechanism comprising the combination of a guide extending alongside a stretch of track, braking mechanism movably supported thereon for engagement with a track rail, operable
- 45 means for engaging the braking mechanism with the track rail, and means for disengaging the braking mechanism from the rail incident to its movement longitudinally thereon.
- 50 5. In a railway, a braking apparatus com-

prising a guide extending alongside a stretch of track, a braking device movably supported on the guide, said braking device being movable along the rail by pressure from a car travelling thereon, operable means effective at a setting station to shift the braking device into cooperation with the rail, throw-off devices associated with the rail to disengage the braking device therefrom, and means operable to restore the braking device to the setting station.

6. In a railway, a braking apparatus comprising the combination of a guide extending longitudinally of a stretch of track, a braking device movably supported thereon for association with a track rail, means for shifting the braking device into and out of cooperation with a rail, and latching means for maintaining the braking device in cooperation with a rail.

7. In a railway, a braking apparatus comprising the combination of a guide extending longitudinally of a stretch of track, a braking device movably supported thereon for association with a track rail, means for shifting the braking device into and out of cooperation with a rail, latching means for maintaining the braking device in cooperation with a rail, and means for moving the braking device on the guide longitudinally of the track.

8. In a railway, the combination with a track rail of a braking device mounted for movement along the rail under pressure from a car thereon, operative means at a setting station effective to position the braking device on the rail, throw-off means effective beyond the setting station to disengage the braking device from the rail and means for restoring the braking device from the place of disengagement to the setting station.

9. In a railway, the combination with a track rail of a braking device movable thereon under pressure from a car travelling on the rail, setting mechanism for disposing the braking device on the rail, throw-off means for disengaging the braking device from the rail, and mechanism for shifting the throw-off means to effective and ineffective positions.

10. In a railway, the combination with a track rail of a braking device arranged to ride on the rail, setting mechanism operable to dispose the braking device on the rail, throw-off means for disengaging the braking device from the rail, and means for restoring the braking device to operative association with the setting mechanism.

11. In a railway, a braking apparatus comprising a guide extending longitudinally of a stretch of track, a braking device movable thereon for association with a car on the track, setting mechanism and throw-off means effective to move the braking device

- into and out of cooperation with the track, and restoring mechanism for moving the braking device longitudinally of the track.
12. In a railway, the combination with a track rail of a shoe adapted to rest thereon and support the wheel of a car travelling on the track, operable means for maintaining the shoe on the rail, and means for shifting it onto and off of the rail.
- 10 13. In a railway, the combination with a track rail of a braking member adapted to be moved in cooperation with the rail and with a car thereon, mechanism disposed at a setting station for moving the braking member into association with the rail and car, and throw-off means disposed in association with the track for moving the braking member out of cooperation with the track and the car.
14. In a railway, the combination with a track rail of a braking member adapted to be moved in cooperation with the rail and with a car thereon, mechanism disposed at a setting station for moving the braking member into association with the rail and car, throw-off means disposed in association with the track for moving the braking member out of cooperation with the track and the car, and means for shifting the braking member from the throw-off means to the setting station. 20 25 30

In testimony whereof I have hereunto signed my name in the presence of two subscribing witnesses.

HOWARD VAN SCOY.
